(57) **CLAIM**

The ornamental design for a semiconductor driving circuit module, as shown and described.

DESCRIPTION

FIG. 1 is a perspective view of a semiconductor driving circuit module showing our new design;

FIG. 2 is a front view of the semiconductor driving circuit module of FIG. 1;

FIG. 3 is a rear view of the semiconductor driving circuit module of FIG. 1;

FIG. 4 is a left side view of the semiconductor driving circuit module of FIG. 1;

FIG. 5 is a right side view of the semiconductor driving circuit module of FIG. 1;

FIG. 6 is a top view of the semiconductor driving circuit module of FIG. 1;

FIG. 7 is a bottom view of the semiconductor driving circuit module of FIG. 1; and,

FIG. 8 is a perspective view of the semiconductor driving circuit module of FIG. 1 shown in a used condition, mounted on a semiconductor element shown in broken lines.

The broken line portions of the semiconductor driving circuit module in FIGS. 1-8 represent unclaimed portions of the claimed design and form no part thereof. The broken lines in FIG. 8 showing the semiconductor element represent the environment only and form no part thereof.
